UNITED STATES PATENT OFFICE.

EDWARD R. LINEBAUGH, OF BARBERTON, OHIO, ASSIGNOR TO THE DIAMOND MATCH COMPANY, OF CHICAGO, ILLINOIS, A CORPORATION OF ILLINOIS.

SLIP-SHEET MECHANISM FOR PRINTING PRESSES.

Application filed June 16, 1928. Serial No. 285,937.

This invention relates to printing presses, and more particularly to Gordon presses adapted to print relatively large sheets of pasteboard, or the like, which are subsequently subdivided into book-match covers having imprinted outer surfaces. Heavy inking, including gold and other metallic ink, is frequently used for the cover sheets, and hence when the freshly printed sheets are delivered by the press to the stacker bed, the imprinted backs of the superimposed sheets are marked or smeared to a greater or less extent by their contact with the ink on the opposing printed surfaces. This marking or smearing is objectionable, especially when the reverse side of the sheet, which constitutes the inside of the match book covers, is to be subsequently printed.

The object of my invention is to overcome the objection mentioned; and to that end I combine with a printing press simple and efficient means whereby a supplemental sheet, termed a "slip sheet," is placed upon the freshly printed surface of each printed sheet as rapidly as the latter is deposited on the stacker bed of the press; thus separating the opposing surfaces of the superimposed printed sheets.

My invention also comprises novel features of construction and combinations of parts which will be hereinafter described, and the scope of the invention then be defined in the appended claims.

In the drawings—

Figure 1 is a side elevation of a portion of a Gordon press embodying my invention.

Fig. 2 is an elevation of a portion of the opposite side of the press, together with the associated slip-sheet transfer mechanism.

Fig. 3 is a plan of the said transfer mechanism.

Fig. 4 is a view illustrating the position of the slip-sheets during their release above and placement on the printed sheets on the stacker bed.

Fig. 5 is an end elevation of a portion of the press, showing the relation of the slip-sheet tray to the stacker bed, and illustrating the main elements of the slip-sheet mechanism. In this view the pneumatic transfer cup is shown supporting a slip sheet above the stacker bed.

Fig. 6 is a similar view, but showing the transfer cup in raised position supporting a slip-sheet above the tray.

Referring to the drawings, 10 designates the stationary main frame of a printing press of the Gordon type. 11 designates the swinging bed frame of the press, which frame supports the type form at 12, and also the relatively inclined ink distributing disk 13, together with the inking devices and their appurtenances. This frame is actuated by a link and crank connection at each side of the press, one of the cranks being designated 14 and its associated link being designated 15.

16 designates oscillatory take-off mechanism, including grippers 17 operative to grip the upper edge of each succeeding sheet as rapidly as it is printed and transfer the sheet to a suitably-located stacker bed or table 18 on the supporting frame. These grippers are carried by an oscillating arm 19 which is actuated from a driven shaft 20 of the press through interposed cam and gear mechanism in the usual manner.

According to my present invention I arrange in cooperative relation to the printing press automatically operative mechanism whereby a slip sheet (A) is imposed on each succeeding printed sheet (B) when the latter is delivered to the stacker bed. The preferred form of slip-sheet supplying mechanism herein illustrated comprises a suitably elevated tray 21 which is supported between the stacker bed 18 and the printing mechanism of the press, and which tray is adapted to contain a stack of slip sheets A of pasteboard or other suitable material. This tray is supported by a bracket 22 extending from a post 23 rising from the main frame.

24 designates a suction cup which is vertically movable into and above the tray 21, so as to pick up the uppermost slip-sheet from the stack, and which cup, when elevated, is movable in a horizontal path to position the attached slip-sheet directly above the stacker bed. The cup 24 is fast on a depending terminal branch 25 of a horizontally extending pipe 26 which is connected by means of a flexible tube 27 with the usual air line 28 extending from the compressed air reservoir 29 of the printing press. The horizontal pipe 26 is reciprocative in a tubular guide 30 which is pivoted, as at 31, to a vertical post 32 spaced from and secured to the post 23 by an angular foot extension 33. This guide permits not only vertical oscillation of the pipe 26 and its depending branch 25 and cup 24 in respect to the tray, but also

their horizontal reciprocation in a path overlying the tray and the stacker bed.

A preferred means for vertically moving the pipe 26, when the suction cup 24 overhangs the tray, includes a rock-arm 34 which is pivoted at one end to a collar 35 on a basal bend of the post 32, and is pivotally connected at its free end with a depending lug 36 on the guide 30 by means of a link 37. The rock-arm is equipped at its free end with a roll 38 which co-operates with a cam 39 on the shaft 40 of one of the transverse delivery rolls of the press; the roll 38 being held in operative contact with the periphery of the cam by means of a spring 400 which is secured to the lug 36 and to a pin 41 projecting from the post 32.

The cam comprises a disk having a peripheral recess 42 therein, which is so located as to permit and effect a downward and an upward movement of the roll 38 during the delivery of a printed sheet from the printing mechanism to the stacker table, thus producing a similar vertical movement of the air pipe 25 and its suction cup 24. This cup in its vertical movement picks up the uppermost slip sheet contained in the tray and raises the sheet above the tray, as seen in Fig. 6.

A preferred means for horizontally reciprocating the pipe 26, together with the suction cup 24, includes a bell-crank which is fulcrumed, as at 43, to the bracket 22. The shorter arm 44 of the bell-crank is connected eccentrically to the cam disk 39 by means of a link 45 and the longer arm 46 is connected by means of a link 47 with a lug on the outer end of the pipe 26. The crank and link connections just described are so relatively disposed that during the rotation of the cam disk 39, the bell-crank is oscillated in a manner to effect the requisite longitudinal reciprocation of the pipe 26 and the suction cup. At the limit of the outer stroke of the pipe the suction cup, with the attached slip-sheet, is positioned directly over the stacker bed, as seen in Fig. 5. At this instant the connection in the air-line is temporarily interrupted, thus releasing the slip sheet from the suction cup and permitting the sheet to fall flatwise upon the underlying printed sheet on the stacker bed.

As a simple and efficient means to interrupt the air exhaust from the pipe 26 at the proper intervals of time, the tube 27 is equipped with a normally open check valve 48 which is supported by a bracket 49 on the frame 10. The spring-pressed stem 50 of the valve extends into the path of the adjacent crank 14 of the press, as such arm approaches and completes its movement to the left as viewed in Fig. 1, and hence the arm, impinging against the valve stem, temporarily closes the valve. Any other suitable

means for controlling the air exhaust may be employed.

Where, as in the present instance, the pasteboard slip-sheets are of large size, the cup 24 is arranged and adapted to engage each succeeding slip-sheet at a spot somewhat away from the transverse median line of the latter, that is, toward one end of the sheet, as seen in Fig. 3. Consequently the opposite end of the sheet, when it is elevated from the tray, tends to sag to a limited extent. To receive and support such end a horizontal rail 51 is mounted at a suitable level, which rail, in the present instance, has at one end a downward bend 52 that is secured to the adjacent wall of the tray. When a slip-sheet is lifted from the tray by the suction cup, the sheet is at a slightly lower level than the rail, but as the sheet is advanced toward the stacker bed and the end of the sheet remote from the cup contacts with the opposing curved portion 52 of the rail and is thereby cammed above the plane of the portion of the sheet held by the suction cup. The slip-sheet, thus slightly inclined, is carried and positioned over the stacker bed, and hence when the sheet is released from the suction cup, as previously mentioned, the unsupported end of the sheet immediately drops and the other end is withdrawn from the supporting rail, whereupon the slip-sheet, in inclined position, falls and comes to rest upon the underlying printed sheet on the stacker bed, as seen in Fig. 4. In this way the accurate positioning of the slip-sheet on the printed sheet is accomplished.

In an application Serial No. 285,936 filed by me simultaneously herewith I disclose a form of mechanism for automatically supplying slip sheets to consecutively printed sheets, which application contains generic claims embracing the species of the invention herein described and claimed.

I claim—

1. The combination with a printing press, including a stacker bed and means for delivering the printed sheets in succession on said bed, of means for supporting a stack of slip sheets adjacent the press, and transfer means operative in timed relation to the press to remove the slip sheets in succession from the stack, move each succeeding slip sheet in a direction transverse to the movement of the printed sheets and deposit a slip sheet upon each succeeding printed sheet supported on the stacker bed.

2. The combination with a printing press, including a stacker bed and means for delivering the printed sheets in succession on said bed, of means for supporting a stack of slip sheets adjacent the press, and transfer means operative in timed relation to the press to remove the slip sheets in succession

from the stack and deposit a slip sheet upon each succeeding printed sheet supported on the stacker bed, said transfer means including a pneumatic member movable vertically 5 toward and from the stack and horizontally from the stack in a direction transverse to the movement of the printed sheets to a position above the bed, and means for automatically checking the holding operation of the 10 pneumatic member when a slip sheet is located above the stacker bed.

3. The combination with a printing press, including a stacker bed and means for delivering the printed sheets in succession on 15 said bed, of means for supporting a stack of slip sheets adjacent the press, and transfer means operative in timed relation to the press to remove the slip sheets in succession from the stack and deposit a slip sheet upon 20 each succeeding printed sheet supported on the stacker bed, said transfer means including a pneumatic member movable vertically toward and from the stack and horizontally from the stack to a position above the bed, 25 means for supporting a marginal portion of each sheet clear of the stack of sheets during its horizontal travel, and means for automatically checking the holding operation of the pneumatic member when a slip sheet 30 is located above the stacker bed.

4. The combination with a printing press,

including a stacker bed and means for delivering the printed sheets in succession on said bed, of means for supporting a stack of slip sheets adjacent the press, and transfer 35 means operative in timed relation to the press to remove the slip sheets in succession from the stack and deposit a slip sheet upon each succeeding printed sheet supported on the stacker bed, said transfer means including a horizontally movable pipe, a depending suction member thereon movable vertically toward and from the stack of slip sheets and horizontally from the stack to a position above the bed, an oscillatory horizontal 40 guide for said pipe, means for oscillating the guide in a vertical arc to raise and lower the section member, means for horizontally reciprocating the pipe in said guide for moving the suction member to transfer 45 a slip sheet from above the stack of slip sheets to a point above the stacker, means for exhausting air from said pipe, and means for automatically interrupting the flow of air through said pipe when the suction member is located above the stacker bed. 50

Signed at Barberton, in the county of Summit and State of Ohio, this 14 day of June, A. D. 1928.

EDWARD R. LINEBAUGH.
